UNITED STATES PATENT OFFICE.

REUBEN F. BARKER, OF PORTLAND, OREGON.

HOLDING-DOWN MECHANISM FOR ROTARY VALVES.

Original application filed February 5, 1925, Serial No. 7,054. Divided and this application filed July 13, 1925. Serial No. 43,289.

My invention relates to internal combustion engines and has particularly to do with the valve mechanism thereof.

One of the particular objects of my invention is to improve further the rotary valve for explosive engines patented by myself January 1, 1918, Patent No. 1,251,953. This application has been divided out of my co-pending application entitled Rotary valve for internal combustion engines which was filed February 5th, 1925, and receiving Serial No. 7,054.

One of the main objects of my present invention is to provide means adapted to hold that portion of the face of the valve which is adjacent the seat of the cylinder port at the instant of explosion, firmly against said port at least during the instant the gas is ignited in said cylinders so as to prevent gas from escaping into the valve bore of the cylinders. Said means preferably consists of a holding-down mechanism, a part carried by the valve and a part carried by the bore of the cylinder, which is arranged to periodically tend to move said valve towards the cylinder port to seat the same firmly in place and which preferably relieves the pressure during other positions of the valve. I also show devices by which the entire valve is mounted eccentrically to the valve bore, the eccentric throw being arranged to hold the valve in the bore in such a position that it bears tightly against the port at all periods of the cycle. Said devices eliminate the frictional resistance of tight packing about said valve which would otherwise be required.

The further details of construction and the mode of operation of my invention are hereinafter described with reference to the accompanying drawings, in which:

Fig. 1 is a longitudinal section through one of the valve elements showing the holding down devices at each end bearing upon the periphery of said valve between two sealing rings;

Figs. 1^a and 1^b are respectively cross sections through one end of said valve and illustrate diagrammatically two phases of the holding down means provided for applying pressure and resistance to the periphery of said valve opposite the cylinder port, at the instant gas is ignited, said pressure tending to hold the valve closely

against its seat on said port, said pressure being relieved during the other positions of the valve;

Fig. 2 is a longitudinal section through one of said valves similar to Fig. 1, but shows an alternative arrangement for holding the valve down tightly against the cylinder port to prevent leakage of gas from the bore of the cylinder in which the valve rotates;

Fig. 3 is a transverse section taken on the line 3—3 of Fig. 2, and

Fig. 4 is a transverse section taken on the line 4—4 of Fig. 2.

My invention is shown as being embodied in one of the cylinders for an internal combustion engine, the cylinder being designated as 1, the piston 2 and the rotary valve 3. Said valve is journaled in a transverse bore of said cylinder, said bore communicating with the working barrel of the cylinder through a cylinder port 4. Said valve carries a worm gear 5 which is connected to said valve through an Oldham coupling 6. Said worm gears 5 are carried upon a roller bearing 7, said roller bearing being mounted upon a hollow trunnion 8 which is integral with and extends laterally from the housing 9 which constitutes a covering for said couplings, bearings, worm gears, and for the driving shaft 10 which carries the worm 10^a which meshes with the worm gear 5. A tubular water conduit 11 from said valve is also journaled in said housing 9 and packing 12 is arranged at both sides of the radial outlets 13 therein, as shown in Fig. 1. Said housing carries a cooling fluid manifold 14, as shown in said figure, said manifold being provided with outlets 14^a which communicate with the radial outlets 13 which extend through the tubular conduit 11. Within said tubular conduit 11 is a smaller sized conduit 15 which has a flange 15^a at its outer extremity which completely fills the bore of the tubular conduit 11. The bore of said smaller tubular conduit 15 extends completely therethrough and forms a passageway for the cooling fluid which is completely separated from the passageway formed about the periphery of the smaller conduit 15. The inlets 14^b communicate with the bore in said smaller sized conduit 15.

The apertures 14^a and 14^b in the cooling fluid manifold are located at a point above

the major part of the valve so that a substantial amount of cooling fluid will be entrapped within the valve so that if the supply of cooling fluid should become depleted, the cooling fluid thus entrapped would be sufficient to substantially cover the exposed portions of the valve.

The connection passageways 14^c and 14^d which connect said apertures 14^a and 14^b with the respective outlet and inlet ends of the cooling fluid passageway, are arranged vertically and constitute stand pipes adapted to prevent the displacement of the cooling fluid, as previously referred to.

15 Each of said valves comprise a cylindrical body which is provided with a passageway 15 for the incoming gases, a passageway 16 for the exhaust gases, and a continuous passageway 17 adjacent said gas passageways 20 for the cooling fluid. The arrangement of the passageways in this manner permits the heat of the exhaust gases to be removed in part so as to prevent said excessive heat from binding said valves in their seats, due to dis- 25 tortion.

As can be seen in Fig. 1, the intake passageway 15 in each of said valves occupy a cylindrical bore extending substantially through the valve and terminates in a port 30 15^a. Said port opens to the periphery of said valve and occupies a sector of said cylinder, which is substantially one-fourth of the circumference. The exhaust passageway 16 partially surrounds the intake passageway 15 and also terminates in a port which occupies substantially one-fourth of the circumference of said valve.

40 The passageway for the cooling fluid comprises the bore of the conduit 18, which terminates in the passageway 17, which permits the cooling fluid to circulate around the exterior of the exhaust conduit. The cooling liquid is emitted through the radial holes 13 through the stand pipe section 14^c to the outlet aperture 14^d in the manifold 14 for the cooling fluid. The passageway for said cooling fluid thus is continuous through the valve.

50 The cooling fluid enters and is emitted from points adjacent each other at the same side of said valve. The passageway extends through the valve longitudinally from one end to the other and doubles back upon itself. The passageway in said valve for the cooling fluid parallels the passageway for the gases. Said passageways are arranged to remove a substantial portion of the heat from the exhaust gases emitted by the cylinder and the exhaust passageway is arranged relatively to the intake passageway so that sufficient heat is given thereto to partially, if not wholly, gasify the combustible gases passing through said intake passageway, thus to assist in the combustion there- 55 of in the cylinder.

As is shown in exaggerated fashion in Figs. 1, 1^a and 1^b, portions 19 and 20 at the ends of said valve member and at each side of the intake and outlet ports in the valve are arranged eccentric relatively to the remainder of the valve. Said Figs. 1^a and 1^b exaggerate the clearances between the valve and the bore for the purpose of illustration.

70 As shown in said figures, when the intake and outlet ports are arranged diametrically opposite the cylinder port 4, the valve is arranged so that the shoes 21 bear against the eccentric portions 19 and 20 and tend to move the valve towards the cylinder port 4, and thus hold said valve tightly against said port, to prevent leakage thereby. Said shoes 21 are adjustable by placing shims 22 of different thicknesses beneath the holding down brackets 23, said brackets being held in place by studs 24.

75 At each side of the intake and exhaust ports, I mount expansible sealing rings 25 to prevent leakage longitudinally of said valve. Said sealing rings are mounted at each side of the eccentric portions 19 and 20, and provide an 80 extremely efficient sealing device without building up excessive friction to retard the rotation of said valve.

85 In Figs. 2, 3 and 4, I show an alternative arrangement by which the valve 26 may be 90 arranged relatively in the bore 27 in the cylinder 28, thereby to tend to seat tightly against the cylinder port 29 and thus prevent the escape of gases around said valve. In the devices shown in said figures, the 100 valve is arranged to rotate about an axis passing through the point α which is not coincident with the axis of the bore which passes through the point γ . Said valve 26 is mounted in two removable bearings 30 which 105 are shown as containing balls 30^a, but it is to be understood that said removable bearings might consist of tapered roller bearings or sleeve bearings. Said removable bearings are mounted in recesses 31 at the 110 ends of the bore 27. Said recesses are arranged eccentrically, relatively to said bore, thus the valve rotates so that all of its clearance with said bore is at the top of the valve, as shown in Fig. 4. The amount of clearance between said valve and said bore is 115 greatly exaggerated and in practice would hardly exceed ten one-thousandths of an inch and would preferably be approximately about five one-thousandths of an inch. By 120 mounting the valve in this manner, a substantial amount of clearance can be provided about said valve to provide for easy running, but the valves fit very closely 125 against the cylinder port 29 to prevent leakage.

130 The pressure built up within the cylinder, due to the ignition and resultant expansion of the gases, tends to lift the valve off of its seat upon the cylinder port, and also tends to escape about said valve.

I claim:

1. In an internal combustion engine cylinder, a rotary valve provided with ports intermediate its ends, said valve operating in a bore in the cylinder, said valve ports adapted to communicate with a port in the cylinder, cam-shaped devices and portions co-operating therewith carried by said valve and said bore respectively, which are adapted to hold that portion of the face of the valve adjacent the seat of the cylinder port firmly against said seat during the instant the gas charge ignites in said cylinder.
2. In an internal combustion engine cylinder, a rotary valve provided with ports intermediate its ends, said valve operating in a bore in the cylinder, said valve ports adapted to communicate with a port in the cylinder, said valve being provided with a portion eccentric to said bore, the eccentric throw being adapted to hold that portion of the face of the valve adjacent the seat of the cylinder port firmly against said seat during the instant the gas charge ignites in said cylinder.
3. In an internal combustion engine cylinder, a rotary valve provided with ports intermediate its ends, a thrust-resisting element bearing against that face of the valve positioned opposite the cylinder port, said face of the valve and said thrust-resisting element being relatively formed to tend to hold the valve firmly against the seat of the cylinder port at the instant the gas charge is ignited, and to relieve the pressure of said thrust-resisting element on the valve in other positions of the latter.
4. In an internal combustion engine cylinder, a rotary valve provided with ports intermediate its ends, an adjustable thrust-resisting element bearing against that face of the valve positioned opposite the cylinder port, said face of the valve and said thrust-resisting element being relatively formed to tend to hold the valve firmly against the seat of the cylinder port at the instant the gas charge is ignited, and to relieve pressure of said thrust-resisting element on the valve in other positions of the latter.
5. In an internal combustion engine cylinder, a rotary valve provided with ports intermediate its ends, a thrust-resisting element located at each end of the cylinder exteriorly of said ports bearing against that face of the valve positioned opposite the cylinder port, said face of the valve and said thrust-resisting element being relatively formed to tend to hold the valve firmly against the seat of the cylinder port at the instant the gas charge is ignited, and to relieve pressure of said thrust-resisting element on the valve in other positions of the latter.
6. In an internal combustion engine cylinder, a rotary valve provided with ports intermediate its ends, a thrust-resisting element located at each end of the cylinder exteriorly of said ports bearing against that face of the valve positioned opposite the cylinder port, said face of the valve and said thrust-resisting element being relatively formed to tend to hold the valve firmly against the seat of the cylinder port at the instant the gas charge is ignited, and to relieve pressure of said thrust-resisting element on the valve in other positions of the latter.
7. In an internal combustion engine cylinder, a rotary valve, a thrust-resisting element adapted to bear against that face of the valve positioned opposite the cylinder port, said valve provided with a circumferential cavity in which said thrust-resisting element bears in certain positions of the valve, whereby the valve is held firmly against the seat of the cylinder port at the instant the gas charge is ignited, and in other phases is relieved of the pressure of said resisting element.
8. In an internal combustion engine cylinder, a rotary valve, a thrust-resisting element adapted to bear against that face of the valve positioned opposite the cylinder port, said valve provided with a circumferential cam-shaped portion in which said thrust-resisting element bears in certain positions of the valve, whereby the valve is held firmly against the seat of the cylinder port at the instant the gas charge is ignited, and in other phases is relieved of the pressure of said resisting element.
9. In an internal combustion engine cylinder, a rotary valve, a thrust-resisting element adapted to bear against the face of the valve positioned opposite the cylinder port, said valve provided at each of its ends with a circumferential cavity in which said thrust-resisting element bears in certain positions of the valve, whereby the valve is held firmly against the seat of the cylinder port at the instant the gas charge is ignited, and in other phases is relieved of the pressure of said resisting element.
10. In an internal combustion engine cylinder, a rotary valve provided with ports intermediate its ends, said valve operating in a bore in the cylinder, said valve ports adapted to communicate with a port in the cylinder, cam-shaped devices and portions operating therewith adapted to hold that portion of the face of the valve adjacent the seat of the cylinder port firmly against said seat during the instant the gas charge ignites in said cylinder.

REUBEN F. BARKER.
